12 Claims.

(Cl. 60—16)

My invention relates to internal combustion engines and to the operation of such engines. It relates more particularly to means for regulating the turning moment of such an engine, quite especially if the engine is started under load, such as is mostly the case with vehicle driving engines, hoisting engines or other working engines.

According to the present invention these drawbacks are avoided in that, in order to raise the turning moment of internal combustion engines which are as a rule started under load (for instance an engine acting on the vehicle directly without a throw-out and a change speed gearing), the working chambers of the engine are supplied with compressed gases withdrawn from the working chambers of another internal combustion engine operated with a higher number of rotations and which, during this withdrawal of compressed gas, does not as a rule transmit any mechanical energy while in the same cycle of operation fuel is fed to the working chambers of that other engine. On the engine to be started being speeded up sufficiently, the two engines are then coupled with the vehicle, working machine or other device which they are designed to drive jointly. However the two engines are now also operated independently of each other, for instance one in two-cycle, the other in four-cycle operation.

As compared with the known methods mentioned above this invention involves the great advantage that, once the necessary starting speed is attained, the entire engine set mounted for instance on a vehicle is fully utilized for direct drive, without its being necessary to carry along any dead weight. Furthermore no undesirable rise of pressure above normal operation can arise in the driving engine during the supply of additional compressed gas, since no undue percentage of oxygen can occur in the working chambers.

The two engines may be piston engines with an equal or different number of cylinders and with equal or different piston surfaces and piston strokes, but the second engine designed to supply compressed gas for combustion may as well be a gas turbine and in that case the first engine, which for great turning moments, for instance when starting and speeding up a vehicle, is operated with compressed gas, will preferably be a piston engine. However both engines may also be gas turbines. They may be coupled directly and may then operate at equal speed, or they may be operated at different speeds, being coupled by means of corresponding step-up or step-

down gearings, quite especially if a piston engine is coupled with a gas turbine.

In a special embodiment of this invention these two engines may be enclosed in a single engine casing and in that case the engine set presents the outer appearance of a single engine. After the two engines have attained the required number of rotations, their speeds are equalized and the engines coupled with each other, whereupon the transfusion of gas under pressure from one group of working chambers to the other is discontinued and the two groups then operated in the normal way like a single engine.

The regulation of the compressed gas supply and the turning moment depending therefrom can be effected in either of two ways: either the gas under pressure may be fed to the working chambers of the first engine at a pressure kept approximately constant, the quantity of compressed gas fed in being adapted to the performance per cycle required in each individual case. When thus proceeding, the compressed gases are withdrawn from the working cylinders, operating without any delivery of mechanical energy, under the same pressure, while the working cylinders to which the compressed gas is supplied, are provided with an adjustable control for regulating the charge, so that the amount of the charge can be adapted to the turning moment which shall be obtained.

On the other hand it is also possible that the supply of the compressed gas to the working chambers of the first engine is effected under variable pressure, the quantity of compressed gas and the pressure being adapted to performance per cycle required in each individual case. In this method of regulation it is useful to combine the control with the working cylinders of the second engine, from which the compressed gas is withdrawn, so that the required quantity of compressed gas can be withdrawn from the cylinders under variable pressure. In this case it may be useful to operate this control in dependency from the required turning moment of the first engine, and this in such manner that in proportion to the decrease of the required turning moment gases under less high pressure are withdrawn from the second engine and fed to the first engine. Thus the change of pressure of the gas to be supplied occurs in dependency upon the number of rotations of the engine operated with the aid of this gas by adjusting a device which controls the beginning and end of the withdrawal of compressed gas from the other engine.

The second engine which as a rule does not furnish any mechanical energy while more or less gas under pressure is withdrawn under varying pressure, must be limited automatically, by means of a speed governor, to a predetermined maximum speed in order to prevent racing of the engine when less gas is withdrawn. For the operation of this engine under no load, when neither mechanical energy nor compressed gas are withdrawn, it is advisable to influence the automatic speed governor in such manner that a materially lower speed than that permitted by the governor during normal operation can be maintained, in order to avoid idle running at maximum speed and unnecessary wear of the engine.

In coupling the two engines it is necessary to cause them to run substantially at equal speed, i. e. to reduce the speed of the engine, which hitherto did not deliver mechanical energy, but only compressed gas, to the speed of the other engine. Since the engines must be coupled with each other at altogether different speeds, corresponding to the resistances offered or encountered by the vehicle, the regulation of the coupling speed will preferably be effected arbitrarily in accordance with the conditions of each individual case. It is therefore necessary to provide the speed governor of the second engine furnishing compressed gas with an arbitrarily operable adjusting device serving to render the numbers of rotation of the two engines equal. Thus in this case the engine, from which compressed gas is withdrawn, will tend to operate at maximum speed until its speed is reduced, for the purpose of synchronisation, by arbitrarily influencing the spring forming part of its governor.

In contradistinction thereto it is also possible to enforce on the second engine, which furnishes the compressed gas, another speed characteristic by equipping its governor with an adjusting device operating in dependency on the speed of the first engine, which is fed with the compressed gas, this adjusting device, when the number of revolutions of the engine rises, also influences the governor in the sense of an increase of speed up to a maximum. Since in proportion to the increase of speed of the first engine, fed with compressed gas, the consumption of compressed gas rises also, the governor of the second engine is influenced in the sense of an increase of speed also in dependency on the speed of the first engine, in order to enable more compressed gas to be withdrawn. Also in this case a further adjusting member acting on the governor must be provided for the purpose of arbitrarily equalizing the speed of the two engines about to be coupled with each other.

In the drawings affixed to this specification and forming part thereof several embodiments of this invention are illustrated diagrammatically by way of example.

In the drawings

Figs. 1 and 4 illustrate, in a purely diagrammatic manner, two examples of two-cycle engines and the means for controlling same, each engine being represented, for the sake of simplicity, only by one working cylinder.

Figs. 2, 3, 5 and 6 show diagrams illustrating changes of turning moments and speed.

Referring to the drawings and first to Fig. 1, 1 and 2 are the two engines, the engine 1 being permanently coupled with the vehicle (not shown) at 33. 4 and 3 are the fuel pumps, feeding fuel to the engines 1 and 2, respectively.

The quantity of fuel supplied to engine 2 through pipe 36 is varied by a centrifugal governor 5, driven by the crank shaft 62 of this engine, through rods 6 and 7. The governor spring 8 can be influenced by means of a hand lever 9 when it is desired to arbitrarily vary the maximum speed limited by the governor. The mechanism controlling the fuel pump 4 is influenced by a spring 10, hood 60 and rack 61 for a supply of fuel corresponding to operation under full load. The fuel is here supplied by pump 4 through pipe 38 to the engine 1. Besides the normal intake and exhaust ports 11 and 12, respectively, the cylinders of engine 2 are also provided with positively controlled gas delivery valves 13. The engine 1, besides the normal intake ports 14 and exhaust ports 15, is also provided with feed valves 16 for compressed gas. The valves 13 and 16 are actuated by means of separate controlling mechanism (cam shafts 17, 19, driven by the crank shafts 62, 63, levers 18, 20 and adjusting members 21, 22, respectively). Between the two crank shafts a disengageable clutch 23 is provided. A hand-operated lever 24 allows disengaging this clutch by means of rods 25, 26 and at the same time controlling, by means of rods 27 and 28, the gas delivery and gas feed valves 13 and 16, respectively, and, by means of rods 29, 30, 31, regulating the quantity of fuel supplied by the pumps 3 and 4, respectively. Of course it is not necessary that all these devices should be actuated by a single lever; a plurality of actuating means, operable independently of each other, may be provided.

The operation of the combination of engines shown in Fig. 1 is as follows:

Lever 24 is shown in inoperative position; if it is moved through position *a* into position *a*₁, the clutch 23 is disengaged by means of levers 25, 26, so that while now engine 1 is permanently coupled with the vehicle to be driven, engine 2 can be started in a well known manner by pneumatic or electrical means, indicated at 64 in a conventional manner, and can operate under no load without delivering mechanical energy. At the same time the governor 5 adjusts by means of the rods 6 and 7 the fuel pump 3 in such manner that during no load operation a predetermined speed is not exceeded. In order to be able to influence this no-load speed of engine 2, the lever 9 is so moved that the governor spring 8 is expanded and the governor weights already adjusted at a lower speed. In the position *a*₁ of lever 24 the valves 13 and 16 are not yet actuated. However, when the lever is moved into the position *b*, the movement of the adjusting members 21 and 22 causes the ends of the valve control levers 18 and 20, respectively, to be shifted, whereby the cam shafts 17 and 19 cause the valves 13 and 16, respectively, of the two engines to be actuated. Now at a predetermined point of each cycle a predetermined quantity of compressed gas is withdrawn from engine 2 through valve 13, this gas being fed to engine 1 through pipe 37 and valve 16. The gas on expanding in this engine causes the engine and the vehicle coupled with it to start. Since by releasing the governor 5 the number of revolutions of the engine 2 can be adjusted by means of the governor 5 for maximum speed, only a comparatively small quantity of compressed gas need be withdrawn per cycle from engine 2 through valve 13, and this small quantity of compressed gas, in view of the very low number of revolutions of engine 1 during start-

ing, nevertheless ample fills the cylinders of this engine and produces a great turning moment. The degree of filling, i. e. the point at which valve 16 opens, can be adjusted arbitrarily by means of the cam face 32 of member 22 by moving lever 24 between the positions *b* and *c*. Of course the two engines might also be operated as four-cycle engines with a corresponding control of intake and exhaust ports instead of the slot control usual in two-cycle engines.

Fig. 2 illustrates pressure-volume diagrams of a working cylinder of engine 1. If this engine is operated as a normal two-cycle engine without an extra supply of compressed gas, i. e. without valve 16 being actuated, the operating plane of the diagram is enclosed between the curves *d* and *e*. In that case after compression according to curve *d* the injection and combustion of fuel and the expansion of the compressed gases occurs according to curve *e*. For the first starting stroke of the engine however compressed gas is supplied through valve 16 only according to curve *f*, whereby a very complete diagram and consequently also a high turning moment of the engine is produced. Obviously, as long as compressed gas is fed to the engine 1, the normal supply of fuel need not be started. However in order to obtain the highest possible performance, it is advisable to supply and ignite fuel in the normal manner already during the next following cycle, so that then, after compression according to curve *d*, during the working stroke of the piston the combustion of fuel takes place first according to curve *g*, whereupon compressed gas withdrawn from the engine 2 is supplied according to curve *f*. By moving the lever 24 between the positions *b* and *c* the degree of filling per stroke may now be regulated, so that in the pressure-volume diagram the curves *f*₁, *f*₂, *f*₃ etc. are obtained, which indicate a gradually decreasing turning moment. When the required number of revolutions of the engine and a certain speed of propulsion of the vehicle have been attained, the withdrawal of compressed gas from engine 2 and its supply to engine 1 may now be discontinued, and by returning the lever 24 into its position *a* the two engines may now be coupled directly together with the vehicle such as a locomotive. By this operation the two adjusting members 21, 22 are shifted again to the extent of discontinuing actuation of valves 13 and 16. The two engines mounted on the vehicle now operate as normal two-cycle driving engines without any separate engine set being required to be carried along on the vehicle as dead weight. The regulation of the engine is now effected by means of lever 24 within its different positions from zero position down to position *a*, the fuel pumps 3 and 4 being adjustable through rods 29, 30, 31, respectively. Whenever, in consequence of an increased resistance, for instance when climbing an incline, the starting turning moment is again required to be increased, the clutch coupling the two engines may be released and the second engine may again be operated with a high turning moment, similarly as during the start, by an additional supply of compressed gas.

While according to Fig. 2 the compressed gas is withdrawn from the engine 2 at a uniform position of the pistons and thus also under approximately uniform pressure, being thus supplied to the engine 1 under uniform pressure also, the turning moment being regulated by varying the degree of filling, Fig. 3 illustrates another mode of regulation, according to which the compressed

gas is supplied with an approximately uniform degree of filling, however under different pressures indicated by the curves *g*₁, *g*₂, *g*₃, *g*₄ etc.

The arrangement and operation of the control mechanism required therefor is shown in Fig. 4, which agrees with Fig. 1, excepting only the adjusting members 21 and 22, which have changed places here. While according to Fig. 1 within the adjusting limits *b*—*c* of lever 24 no change occurred in the control of the delivery valve 13 which thus opened and closed always at the same crank angle, since the adjusting member 21 is formed with a constant face 34 and, in contradistinction thereto, the face 32 of adjusting member 22 continuously rises within the limits *b*—*c* and thus provides for a steadily increasing opening period of valve 16, according to the modification shown in Fig. 4 the intake valve 16 is always opened and closed, throughout the regulation range *b*—*c*, at the same crank angle, and here the adjusting member 21 of this valve is formed with a constant face 134. On the other hand the crank angle, within which the delivery valve 13 is opened, is varied in dependency upon the inclined control face 132 of the corresponding adjusting member 122, so that the quantity and pressure of the gas withdrawn from the engine 2 during each cycle can be regulated.

Fig. 5 illustrates the variation of the speeds of the two engines plotted above the vehicle speed. Here the number of rotations of the engine 1 coupled directly with the vehicle rises according to line *h* in proportion to the vehicle speed, while the number of rotations of the engine 2 is maintained by the governor 3 at a constant value according to line *i*, after the expansion of the governor spring 8 by lever 9, whereby the number of rotations had been lowered for idle running, has been terminated. The two speed lines *h* and *i* now meet in a point *k*, to which corresponds a predetermined vehicle speed. Since at this point the two machines have attained equal speeds, the moment is now reached for throwing in the coupling 23 and thereby passing over to normal operation of the two engines. In the operation of vehicles meeting with ever varying resistances it is however preferable not to once for all fix the moment of throwing in the clutch on a speed corresponding to the point *k*, but to render it variable according to the varying conditions of travel. To this end therefore the speed of the engine will be influenced arbitrarily, by influencing the spring 8 of governor 5 (Fig. 1) by means of lever 9 in such manner that a lowering of the speeds according to the curves *l*, *l*₁, *l*₂ can be effected selectively, so that already at lower speeds of the engines, corresponding to points *k*₁, *k*₂, *k*₃, and thus also at lower vehicle speeds the two engines can be coupled with each other.

Fig. 6 illustrates a characteristic of the speed of engine 2 differing from the characteristic in Fig. 5. Here the control is effected in such manner that in proportion to a rise of speed of engine 1 and corresponding rise of gas consumption in this engine per unit of time there arises also a rise of speed of engine 2 from idle running speed up to maximum speed. To this end there are provided according to Fig. 4, gyrating masses 40 changing their angular position in dependency on the speed, which influence by means of a rod system 41, 42 the spring 8 of governor 5, so that in proportion to the rise of speed according to line *h* of engine 1 also engine 2 is operated according to line *m* at rising speed up to a maximum speed. In this case the ratio of the speed of engine 1 at the moment,

where engine 2 has just attained its maximum speed, to this maximum speed should be so chosen that engine 2 can still deliver a sufficient quantity of compressed gas that engine 1 still receives the highest possible charge (curve f in Fig. 2). Also with this mode of speed regulation it is advisable to render the speed of engine 2 equal to that of engine 1 if desired, already at lower vehicle speeds by thus influencing the spring 8 of governor 5, that the speed of engine 2 varies according to curves o_1 , o_2 , o_3 or o_4 and that thus equal speeds of the two engines are reacted already at the points n_1 , n_2 , n_3 , n_4 .

I wish it to be understood that I do not desire to be limited to the exact details of construction shown and described for obvious modifications will occur to a person skilled in the art.

I claim:

1. The method of operating an internal combustion engine which as a rule is required to start under load, which comprises feeding to the working space of this first engine, for the purpose of raising its turning moment, compressed gases of combustion withdrawn from the working space of a second internal combustion engine running at higher speed and which as a rule during such withdrawal, does not perform any mechanical work, feeding fuel to the working spaces of said first engine and coupling the two engines, after they have attained a sufficiently high speed, with the device to be driven by them jointly and now operating them independently of each other.

2. The method of claim 1 wherein the feeding of fuel to the first engine takes place before the feeding thereto of compressed gases of combustion.

3. The method of claim 1, in which the compressed gases of combustion from the second engine are fed to the working space of the first engine at approximately constant pressure and in a quantity adapted to the performance required per cycle in each individual case.

4. The method of claim 1, in which the compressed gases of combustion from the second engine are fed to the working space of the first engine at variable pressure and the quantity and pressure of the gas is adapted to the performance required per cycle in each individual case.

5. The method of claim 1, in which the compressed gases of combustion from the second engine are fed to the working space of the first engine at variable pressure and the quantity and pressure of the gas is adapted to the performance required per cycle in each individual case, the pressure being varied in dependency on the speed of the first engine by changing the moments of the beginning and end of compressed gas withdrawal from the second engine.

6. In a device of the kind described in combination, two internal combustion engines, a device to be driven by and directly coupled with the first of said engines, means for withdrawing from the second engine compressed gases of combustion and for feeding said gases to said first engine, means for simultaneously feeding fuel to said first engine and means for arbitrarily coupling also said second engine with the device to be driven.

7. In a device of the kind described in combination, two internal combustion engines, a device to be driven by and directly coupled with the first of said engines, means for withdrawing from the second engine compressed gases of combustion and for feeding said gases to said first engine, means for feeding fuel to said first engine before feeding

it to the compressed gas from said second engine and means for arbitrarily coupling also said second engine with the device to be driven.

8. In a device of the kind described in combination, two internal combustion engines, a device to be driven by and directly coupled with the first of said engines, means for withdrawing from the second engine compressed gases of combustion and for feeding said gases to said first engine, a speed-responsive governor for automatically adjusting said second engine for a predetermined maximum speed while withdrawing compressed gas from said engine and means for arbitrarily coupling also said second engine with the device to be driven.

9. In a device of the kind described in combination, two internal combustion engines, a device to be driven by and directly coupled with the first of said engines, means for withdrawing from the second engine compressed gases of combustion and for feeding said gases to said first engine, a speed-responsive governor for automatically adjusting said second engine for a predetermined maximum speed while withdrawing compressed gas from said engine, means for influencing said governor, while said second engine is running idle, for admitting a materially lower than the normal operating speed and means for arbitrarily coupling also said second engine with the device to be driven.

10. In a device of the kind described in combination, two internal combustion engines, a device to be driven by and directly coupled with the first of said engines, means for withdrawing from the second engine compressed gases of combustion and for feeding said gases to said first engine, a speed-responsive governor for automatically adjusting said second engine for a predetermined maximum speed while withdrawing compressed gas from said engine, arbitrarily operable means for adjusting said governor for a predetermined maximum speed and means for arbitrarily coupling also said second engine with the device to be driven.

11. In a device of the kind described in combination, two internal combustion engines, a device to be driven by and directly coupled with the first of said engines, means for withdrawing from the second engine compressed gases of combustion and for feeding said gases to said first engine, a speed-responsive governor for automatically adjusting said second engine for a predetermined maximum speed while withdrawing compressed gas from said engine, means influenced by the speed of said first engine for adjusting said governor for an increase of speed and means for arbitrarily coupling also said second engine with the device to be driven.

12. In a device of the kind described in combination, two internal combustion engines, a device to be driven by and directly coupled with the first of said engines, means for withdrawing from the second engine compressed gases of combustion and for feeding said gases to said first engine, a speed-responsive governor for automatically adjusting said second engine for a predetermined maximum speed while withdrawing compressed gas from said engine, means influenced by the speed of said first engine for adjusting said governor for an increase of speed, another means, adapted to be actuated arbitrarily, for adjusting said governor and means for arbitrarily coupling also said second engine with the device to be driven.

HERMANN JÄNICKE.
